[57] CLAIM

The ornamental design for a combined sewing table and cover therefor, as shown and described.

DESCRIPTION

FIG. 1 is a perspective view of a combined sewing table and cover therefor showing my new design,

FIG. 2 is a side elevational view thereof,

FIG. 3 is an end elevational view thereof, and

FIG. 4 is a bottom plan view thereof.

The side and end not shown are mirror images of the side and end shown respectively.

FIG. 1FIG. 2FIG. 3FIG. 4
